F. C. OVERBURY & H. C. PLATTS.
FLEXIBLE CONVEX TILE ROOFING.
APPLICATION FILED APR. 7, 1914.

1,158,267.

Patented Oct. 26, 1915.

UNITED STATES PATENT OFFICE.

FREDERICK C. OVERBURY, OF NEW YORK, N. Y., AND HOWARD CARLETON PLATTS, OF RUTHERFORD, NEW JERSEY, ASSIGNEES TO FLINTKOTE MANUFACTURING COMPANY, OF RUTHERFORD, NEW JERSEY, A CORPORATION OF NEW JERSEY.

FLEXIBLE CONVEX TILE ROOFING.

1,158,267.

Specification of Letters Patent.

Patented Oct. 26, 1915.

Application filed April 7, 1914. Serial No. 830,209.

To all whom it may concern:

Be it known that we, FREDERICK C. OVERBURY and HOWARD CARLETON PLATTS, citizens of the United States, and residents, respectively, of New York, in the county of New York and State of New York, and of Rutherford, in the county of Bergen and State of New Jersey, have invented certain new and useful Improvements in Flexible 10 Convex Tile Roofing, (Case E,) of which the following is a specification.

This invention has for its object to provide a roof covering which can be laid to produce the ornamental effect of tiles.

15 Roofing tiles have heretofore been cast or molded of clay or equivalent composition in rigid form and produce an appearance of solidity and a highly ornamental effect when in keeping with the architectural design of the building. Such tiles, however, are relatively expensive to the user both on account of the cost of production, the breakage, and the weight which adds to the cost of transportation.

20 Our purpose is to produce a flexible non-metallic tile, which can be produced in large quantities at low cost, which is waterproof and weatherproof and substantially fire-proof, which can be produced in different colors, and which is light in weight and easily laid.

On the drawing,—Figure 1 shows a portion of a roof provided with tiles embodying our invention. Fig. 2 shows another 25 form of the tile embodying our invention. Fig. 3 shows how the tiles may be bent at the eaves. Fig. 4 represents a cross section through a tile and illustrates a crimped or ribbed blank for supporting the convex portion of the tile. Fig. 5 represents a perspective view of the ribbed blank. Fig. 6 shows the tile itself as provided with a portion which supports the convex portion thereof. Fig. 7 represents a cross section at the ridge 40 of the roof. Fig. 8 shows a magnified section through a bent portion of one of the tiles. Fig. 9 represents a longitudinal section through a vertical row of tiles.

In carrying out our invention, we form 50 the tile blanks of a flexible non-metallic waterproof and weatherproof material. This material consists of a base or foundation of wool felt or equivalent material, preferably saturated or impregnated with a

waterproof compound, such as a hydrocarbon having a relatively low melting point. One or both sides of the blank is coated with a relatively thick coating or layer of weatherproof material, such as a pitch or bitumen having a relatively high melting point so that it will not be affected by solar heat. This outer coating is preferably applied after being heated to a soft and plastic state, but it may be mixed with a volatile solvent and applied cold. Any suitable composition, which will serve the purpose, may be employed for the outer facing or coating. Preferably, the coating substance or compound has thoroughly mixed with it a suitable inert pigment, such, for example, as ground hematite ore, to color it and to add the fire-resistant qualities of the tile.

When a blank or weatherproof covering is made as we have described, it is flexible and pliable, but, after the coating has set or hardened, it cannot be bent at a sharp angle without danger of cracking and breaking the outer coating, a fact which is recognized by those familiar with this art. But we have found that, when the coating is soft and plastic, either by being heated or treated with a solvent, the material may be bent at a sharp angle so as to stretch or elongate, without cracking or breaking, the coating or facing, and that, if the stretched or elongated coating be allowed to set or harden, there is formed what may be termed a hinge, at the bend; and that, when the material is subsequently bent back and forth about the line of the hinge, the coating will not break or crack.

We have illustrated conventionally in Fig. 8, a portion of a sheet, somewhat magnified, in which the impregnated body *a* has the two coatings or facings *b*, *c* of weatherproof compound. When the material is bent, the outer coating is stretched or elongated at *b'* and is compacted and corrugated at *c'*. When the coatings have been permitted to set or harden, the sheet may be straightened without cracking the coating at *b'*.

Preferably the felt foundation is either "two ply" or "three ply", so called, but, in either event, it is thin as compared with a clay tile, and when laid would not form marked division lines between the tiles of a vertical row, *i. e.*, a row of tiles extending from the eaves toward the ridge. To over-

come this defect, we have found that, by bending under the lower portion of the tile to form a fold in the material, an edge of sufficient thickness is produced to form a shadow, and to give the tile an appearance of considerable thickness and solidity.

On the drawings, the supporting wooden structure of the roof is indicated at 10, and upon it are placed the tiles in what may be termed horizontal and vertical rows. Each tile consists of a blank of the material described, said blank being substantially rectangular in shape. While the coating is soft and plastic, its lower edge portion is folded under the body portion thereof, and then, by any suitable means, the tile is bent into shape and the coating permitted to set. As shown in Fig. 1, the blank at one side portion is bent or folded at 12 and 13 to form an upstanding angular rib, and at the other side portion at 13, 14 and 15 to form an angular rib and an upstanding marginal portion 22. Between the ribs, the tile is bent to form a wide convex curved body portion 16. In laying the tiles, the side portions are interlocked or interfitted, so that water is prevented from working between them. With a tile of this nature, *i. e.*, one of non-metallic flexible or pliable material, we provide means for sustaining and supporting the curved body portion. The supporting means may consist of wooden strips placed upon the roof structure or supports formed of flexible material such as that of which the tiles are made, or supports forming integral portions of the tiles themselves. Wooden bars or strips are indicated at 17 in Figs. 1 and 2. In Figs. 4 and 5, the supports are made of sheets or strips which are bent or folded on longitudinal lines to form flat side edges which may be secured to the roof structure and one or more upstanding angular ribs 19 with which the concave surfaces of the wide curved ribs 16 engage. But, as shown in Fig. 6, the rib supports may be formed integrally with the tile, in which case the tile is bent under upon itself at 20, and the bent-under portion is so formed as to provide the upstanding angular ribs 21, 21 under the curved rib 16 and with the portions conforming to and fitting under the angular ribs of the body portion of the tile.

In laying the tiles, the supports for the curved ribs (if separate from the tiles) are first secured to the roof structure in parallelism at the proper distance from each other. Then a horizontal row of tiles is placed on the roof with the side portion of one overlapping the side portion of the one on the right thereof. They may be laterally overlapped, as shown in Fig. 1, so that the angular rib on the right side portion of one lies within or under the angular rib on the left side portion of the other, so that between the

wide curved ribs there is a single angular rib. Or, if desired, they may be laid as shown in Fig. 2, in which case the marginal edge portion 22 extends into the concavity formed by the angular rib of the next adjacent tile, so that two angular ribs are provided between the adjacent curved ribs. As the tiles are laid, nails or other fastenings are driven through the upper portions of the tiles at any convenient points, as indicated at 23, where they will be covered by the tiles of the next higher horizontal row. Then the next horizontal row of tiles is laid in the same manner, but so as to overlap the tiles already laid and so as to cover the nails or other fastenings by which the latter were secured in place. The tiles of each succeeding row are laid so that the angular and curved ribs register with those of the preceding row. When the ridge is reached, the ridge is covered by overlapping tiles 24, the side portions of which are folded back and forth as shown in Fig. 7 to form thick edges, and secured by fastenings 25.

At the eaves, the lower portions of the tiles of the first row are slit along the lines of the bends 13 and 14 to form two flaps 26, 27 which are bent at 28, 29 so as to overlap, as shown in Fig. 3, to close the recess formed by the ribs, and their corners are secured to the end of the roof structure 10 by fastenings 30. They are also slit and bent to form overlapping flaps 31, 32 and 33 to close the recess formed by the curved ribs, and said flaps are fastened to the roof structure. The flaps may be riveted together at 34, or nailed to the support 17, and the flaps 31, 32 may be nailed to the end of the roof structure as shown at 35, 36.

A roof provided with tiles as described is ornate, and presents an appearance of thickness and solidity. The tiles are easily laid without requiring great skill and without the expenditure of much time, as will be readily appreciated. The degree of curvature of the curved ribs may be varied by placing the supports at different distances from each other, and thus having the angular ribs closer together or farther apart.

For shipment, the tiles may be flattened and packed together, without danger of cracking or breaking the coatings thereon. The folded-under portions of the tiles so strengthened and stiffened them that they maintain the ribs in their curved contours, after they are once secured in place.

Having thus explained the nature of our said invention, and described a way of making and using the same, although without attempting to set forth all of the forms in which it may be made or all of the modes of its use, what we claim is:

1. A laterally extensible roofing tile formed of non-metallic flexible material coated with a waterproof compound, said

tile having a folded-under lower edge portion, side portions bent to form upstanding ribs, and an intermediate upstanding convexly curved rib, said ribs being substantially parallel and extending transversely to the folded-under lower edge.

2. A roof comprising a plurality of parallel spaced supports, and a plurality of non-metallic flexible tiles each having a coating of waterproofing compound, said tiles being laid in horizontal rows with one row overlapping the preceding row, and with the tiles of each row laterallylapping each other, said tiles having convex curved ribs bridging said supports.

3. A roof comprising a plurality of non-metallic flexible fibrous tiles each having a coating of waterproofing compound, said tiles being laid in horizontal rows with one row overlapping the preceding row, each tile having lapped side portions bent to form flexibly connected upstanding ribs, and having an intermediate convexly curved upstanding rib, the several ribs of the tiles in one row overlapping and forming continuations of the ribs of the tiles of the preceding row or rows.

4. A roof comprising a plurality of non-metallic flexible tiles each having a coating of waterproofing compound, said tiles being laid in horizontal rows with one row overlapping the preceding row, each tile having lapped side portions bent to form upstanding ribs, and having an intermediate convexly curved upstanding rib, the several ribs of the tiles in one row overlapping and

forming continuations of the ribs of the tiles of the preceding row or rows, and parallel supports beneath the curved ribs and concealed thereby.

40

5. A roof comprising a plurality of non-metallic flexible tiles each having a coating of waterproofing compound, said tiles being laid in horizontal rows with one row overlapping the preceding row, each tile having lapped side portions bent to form upstanding ribs, and having an intermediate convexly curved upstanding rib, the several ribs of the tiles in one row overlapping and forming continuations of the ribs of the tiles of the preceding row or rows, and parallel supports of flexible material bent to form ribs which support and are concealed by said curved ribs.

6. A roof comprising a plurality of tiles formed of flexible non-metallic material coated with a waterproof compound, said tiles being arranged in horizontal rows and with lapping side edges, and with their lower ends overlapping the upper portions of the tiles of the preceding row, said tiles being formed with upstanding ribs, and with underfolded lower edge portions extending from one side edge to the other.

In testimony whereof we have affixed our signatures, in presence of two witnesses.
